(57) **CLAIM**

I claim the ornamental design for a rectangular bird feeder with a solar powered set, as shown and described.

DESCRIPTION

FIG. 1 is a first side view of the rectangular bird feeder with a solar powered set;

FIG. 2 is a second side view thereof;

FIG. 3 is a back view thereof;

FIG. 4 is a front view thereof;

FIG. 5 is a top view thereof; and,

FIG. 6 is a bottom view thereof.
